[57] CLAIM

The ornamental design for a package with product inside, as shown and described.

DESCRIPTION

FIG. 1 is a front elevational view of a package with product inside, showing my new design.

FIG. 2 is a rear elevational view thereof.

FIG. 3 is a right side elevational view thereof.

FIG. 4 is a left side elevational view thereof.

FIG. 5 is a top plan view thereof; and,

FIG. 6 is a bottom plan view thereof.

Our new design includes an outer container having areas of opacity, transparency and translucence, the latter being shown by stippling, and including also product containers within the outer container.

1 Claim, 4 Drawing Sheets
